UNITED STATES PATENT OFFICE.

LINWOOD F. JORDAN, OF PORTLAND, MAINE.

REMOVABLE WHEEL-RIM.

1,299,352.

Specification of Letters Patent. Patented Apr. 1, 1919.

Application filed October 19, 1915. Serial No. 56,790.

To all whom it may concern:

Be it known that I, LINWOOD F. JORDAN, a citizen of the United States, residing at Portland, in the county of Cumberland and State 5 of Maine, have invented certain new and useful Improvements in Removable Wheel-Rims, of which the following is a specification.

My invention relates to improvements in 10 removable rims for vehicles.

In the drawing herewith accompanying and making a part of this application I have shown some embodiments of my invention which seem at the present time to be preferable forms, but other specific embodiments which are within the spirit and scope of the claims herewith may be employed.

In said drawings Figure 1 is a side elevation of a wheel having the usual felly with 20 my improvement applied thereto; Fig. 2 is a perspective view of a portion of a wheel showing a rim adapted to be used with a straight side shoe; Fig. 3 is a perspective view of a portion of a clincher rim embodying my invention; Fig. 4 is a plan view of a recessed felly band or permanent rim; Fig. 5 is a plan view of a portion of my improvement of the form shown in Fig. 2; Fig. 6 is a detail view showing clamps for securing 30 the rim sections when used on a wheel having wire spokes; Fig. 7 is a detail view showing a bottom plan of the meeting ends of the clamps shown in Fig. 6, and Fig. 8 is a perspective view showing a different embodiment of my invention.

Same reference characters indicate like parts in the several figures.

The object of my invention is to provide a removable rim which may be easily and 40 quickly mounted and demounted and which is simple in construction and economical.

In said drawings 1 is a wheel felly, 2 spokes, 3 a shoe and 4 retaining rings adapted to be used with straight side shoes. These 45 may be of any desired construction and in themselves form no part of my invention.

My invention consists in forming the felly band 5, or in case of wire spoke wheels, the permanent rim 6, with recesses 7 in the sides 50 thereof. The removable rim is made in two similar sections having outwardly extending shoe retaining flanges 8 and inwardly extending flanges 9 adapted to take into recesses 7 in the felly band or in the permanent 55 rim, as the case may be. Each rim section is

provided with projections 10 and notches 11 adapted to engage a similar projection and notch structure in the other member. The members when assembled form a substantially continuous rim as shown in Fig. 5. 60 The rim members are held in place by means of clamps 12 adapted to engage the side of each of the sections and bolts for holding the clamps in place. When my invention is used in connection with the felly and felly 65 band the bonding bolt passes through the felly as seen in Fig. 2, and when used in connection with a wire spoke wheel the clamps are provided at the bottom with horizontal inwardly extending parts 14 which preferably engage a projection and groove structure as seen at 15. In this case the bonding bolt passes under the permanent rim as seen in Fig. 6. Outside the removable rim between the flanges may be placed a circular 70 band 16. The felly band may or may not project slightly beyond the felly, as desired.

In Fig. 8 is shown a form of my invention in which there is only one removable member of the rim, the felly band or permanent rim 80 being provided with notches to receive the projections of the removable member.

To mount my rim one member of the rim is placed upon the felly band or permanent rim laterally until the flanges 9 enter the recesses 7. The retaining band 16 is then placed in position and then the other rim member is inserted laterally under the band 16, the projections on one member entering the notches in the opposite member and the 90 downwardly extending flanges 9 entering the recesses in the felly band or permanent rim, as the case may be. The clamps are then placed in position and tightened in the usual manner, preventing lateral separation of the 95 removable rim members. To remove the shoe it is only necessary to remove the clamping members on one side and the outside rim section is then removed laterally.

I claim:

1. A vehicle wheel rim comprising two members capable of lateral separation, the adjacent edges of said members having a mutual projection and notch engaging structure extending entirely across the base of the members and provided with a plurality of wheel engaging flanges.

2. A vehicle wheel having a fixed rim of uniform diameter and a removable rim comprising two members capable of lateral sepa- 110

ration, the adjacent edges of said members having a mutual projection and notch engaging structure, the projections of both members being adapted to rest upon the fixed rim 5 of the wheel and each member provided with integral flanges adapted to engage the edge of said fixed rim.

3. A vehicle wheel having a fixed rim of uniform diameter provided with recesses in 10 the edges thereof and a removable rim comprising two members capable of lateral separation, each member having an integral inwardly extending flange at its outer edge arranged to take into said recesses in the fixed

rim and thereby prevent rotary movement of one rim relative to the other. 15

4. A vehicle wheel comprising a fixed rim of uniform diameter having a plurality of recesses in the edges thereof and a removable rim comprising two members capable of lateral separation, each member having a plurality of inwardly extending flanges at its outer edge arranged to take into said recesses in the fixed rim and prevent rotary movement of the removable rim relative to the 20 fixed rim. 25

In testimony whereof I affix my signature.
LINWOOD F. JORDAN.
